[57] **CLAIM**

The ornamental design for a deck brush handle, as shown and described.

DESCRIPTION

FIG. 1 is a side elevation view of one side of the deck brush handle showing my new design, the opposite side being a mirror image;

FIG. 2 is a top plan view thereof;

FIG. 3 is a bottom plan view thereof;

FIG. 4 is a front elevation view from the left side of FIG. 1; and,

FIG. 5 is a rear elevation view from the right side of FIG. 1. The broken line showing of brush bristles in FIGS. 1, 4 and 5 is for illustrative purposes only and forms no part of the claimed design.
